United States Patent Office

Des. 204,839
Patented May 17, 1966

204,839

LOUVER DAMPER

Robert H. Bishop, 808 W. Park St., Champaign, Ill.

Filed Sept. 1, 1965, Ser. No. 86,792

Term of patent 14 years

(Cl. D62—4)

FIG. 1

FIG. 2

FIGURE 1 is a front perspective view of a louver damper constructed according to the preferred embodiment of my invention, showing the blades of the damper in the fully open position;

FIGURE 2 is a front elevation of the louver damper showing the blades of the damper in the fully closed position;

FIGURE 3 is a plan view of the louver damper; and

FIGURE 4 is a cross-sectional, side elevation along the directions 4-4 of FIGURE 2.

I claim:

The ornamental design for a louver damper, substantially as shown and described.
